UNITED STATES PATENT OFFICE.

GUY L. MEAKER, OF JOLIET, ILLINOIS.

FURNACE FOR GALVANIZING WIRE.

1,208,185.

Specification of Letters Patent. Patented Dec. 12, 1916.

Application filed June 27, 1913. Serial No. 776,150.

To all whom it may concern:

Be it known that I, GUY L. MEAKER, a citizen of the United States, residing at Joliet, Will county, Illinois, have invented a new and useful Furnace for Galvanizing Wire, of which the following is a specification.

In the ordinary process of hot galvanizing to which the present invention relates the iron or steel wire, after having been annealed and cleaned, is fluxed with a suitable compound and passed through a bath of molten zinc or spelter, thus being coated with zinc mechanically while the chemical action of the flux aids in the union of the two metals. For the practice of such process there is ordinarily provided an annealing furnace through which the freshly drawn or "green wire" is passed as the first step in the operation. This furnace ordinarily contains pans or tanks filled with hot lead through which the wire is passed, or brick tubes exteriorly heated through which the wire is led. The wire, after passing through the furnace, is permitted to cool and is then cleaned by pickling, washed, coated with flux and finally passed through the bath of coating metal. Thus the annealing and coating operations are respectively the first and last steps in the treatment and as a consequence require the use of two distinct heating equipments or furnaces. Furthermore, in order to secure the best results, it is desirable to introduce the wire in a highly heated condition into the spelter bath, and this requires a further extension of the heating equipment. Moreover, in the process ordinarily practised there is considerable opportunity for oxidation of the wire by the air, to which it is exposed between the annealing operation and that of coating with the protecting metal, thus materially affecting the efficiency of the operation.

In a companion application Serial No. 776,151 of even date herewith I have described and claimed an improved process for galvanizing or otherwise coating articles and more particularly wire with metal, and more specifically stated with zinc, by which the objections above referred to are largely eliminated and the object of the present invention is a furnace for carrying out the principal steps of that process though some of the features thereof are applicable to other processes as will presently appear.

In the accompanying drawing and in the following specification I have illustrated and described in detail a preferred form of furnace embodying my invention but it will be understood that the specific disclosure is for the purpose of exemplification only and that the scope of the invention is defined in the following claims in which I have endeavored to point out the novelty thereof in such terms as to distinguish it from the prior art without, however, relinquishing or abandoning any portion thereof.

Turning now to the drawing, Figure 1 is a diagrammatic view in side elevation partly in section, showing my improved furnace in connection with other portions of a wire treating apparatus for carrying out the process referred to above; Fig. 2 is a vertical longitudinal central section partly broken away to permit more convenient illustration upon the single sheet of drawing and certain parts being shown in elevation; and Fig. 3 is a section of a detail.

Referring first to Fig. 1, the wire to be treated is supplied from a requisite number of reels A depending on the capacity of the furnace and is led over a guide B through a pickling tank D, a washing tank E and a fluxing tank F, all grouped beneath a suitable hood C as shown. From the fluxing tank the wire is led around a roll G and back through the hood, where the flux thereon is dried by the hot air and gases arising from the tanks, and thence to the furnace. The latter is simply shown in Fig. 1 as comprising the heating section H and a coating tank K but the details of the furnace which constitute the subject matter of the present application are shown in Figs. 2 and 3.

The furnace is constructed of fire brick or other suitable material and comprises a fire box 3 of ordinary construction having the grate bars 4 and connected through openings 11 with a horizontal flue 7 which forms the heating chamber for a series of tubes 20 to be hereinafter described. From the chamber 7 a downtake 10 leads to a lower horizontal flue 12 and from the latter an uptake 13 leads the gases and products of combustion to a horizontal flue 14 provided with suitable baffles 15. From the horizontal flue 14 the gases are conducted by a downtake 16 to a flue 17 which leads to the stack not shown. Air for combustion is supplied to the fire box 3 through an entering flue 6 which, as shown, is protected by a perfo-

rated plate 6' and divides into a pair of branch flues 9 (see dotted lines Fig. 2) arranged respectively on opposite sides of the downtake 10 and joining again in a central flue 5 by which the air is conveyed beneath the grate bars of the fire box.

At 18 is shown a supplemental fire box which ordinarily is employed only in starting the furnace in order to reinforce the heat derived from the fire box 3 beneath the spelter tank K. The latter is arranged above the horizontal flues 14 and 19 and the fire box 18, its bottom being directly exposed thereto. The heating and annealing tubes 20, referred to above, communicate with said tank and abut against the wall thereof, being secured in position by bushings 22 extending through registering openings in the tank and provided with flanges on the inside thereof. At their entrant ends the tubes are inclined upwardly to facilitate the entrance of the wire and throughout their length to a point adjacent their outlet ends are preferably provided with partition walls 21 (see Figs. 2 and 3) which divide the tubes into compartments each of which receives a single wire, thus facilitating uniform heating thereof. Any number of these tubes may be employed side by side depending upon the capacity of the other apparatus employed with the furnace.

The spelter tank contains a bath comprising two layers, the lower of which is composed of lead and the upper of spelter or zinc, the lead also extending into the annealing tubes 20 to a point near the entrant ends thereof. The spelter being the lighter metal of course floats upon the lead. The wires from the cleaning and fluxing tank enter the tubes and pass through the bath of lead which is heated to an annealing temperature in the tubes 20. In that portion of the tubes which passes through the air space 6 the temperature is somewhat reduced, however, and the temperature of the wire is further reduced in the lead bath in the spelter tank which, by reason of its remoteness from the fire box and the exposure of the tank to the outside atmosphere, is at a considerably lower temperature than the lead in the annealing tubes. The wire, however, retains a considerable portion of the heat acquired in the tubes when it enters the spelter which is at an even lower temperature than the lead in the tank by reason of the exposure of its surface to the air. The wire enters the galvanizing bath at a higher temperature than the latter and after receiving its coating emerges and is wound upon a suitable reel. The temperature of the wire is thus gradually reduced from the annealing temperature of the tubes I until it returns to atmospheric temperature thus thoroughly annealing the wire. At the same time the wire is galvanized under the best possible conditions, to

wit, while at a higher temperature than the coating bath. Thus, in my improved furnace, a single heating of the wire is sufficient and a single fire box supplied the heat for both the annealing and the coating operations. The wire is not exposed to oxidation from its entering into the annealing bath until it emerges from the coating bath and it assists in maintaining the temperature of the spelter which it enters at a higher temperature than the latter and therefore in proper condition for securing the best results from the coating operation. The partitions in the tubes 20 not only serve to subdivide them for the purpose stated but also to strengthen them. The lead within the galvanizing tank protects the highly heated bottom thereof from the destructive action of the zinc and the lead being practically covered or inclosed by the spelter and the annealing tubes does not give off the fumes which are commonly so hurtful to those inhaling them.

I claim:

1. In a furnace for coating wire with metal, a tank adapted to contain coating metal, a conduit communicating with the bath at one end and relatively raised at the other and adapted to contain an annealing bath and means for heating said conduit and tank, said means adapted to heat the conduit to a higher temperature at a portion remote from the tank and a lower temperature at the portion nearer said tank.

2. In a furnace for coating wire with metal, a tank adapted to contain the coating metal, a conduit adapted to contain an annealing bath, means for heating said conduit and said tank and means for cooling said conduit at a point adjacent the tank.

3. In a furnace for coating wire with metal, a tank for containing a coating metal, a conduit adapted to contain an annealing bath, a fire box arranged adjacent the end of said conduit remote from the tank, a flue connected thereto and surrounding said conduit and extending beneath said tank and a space between said flue and tank adapted to permit access of air to the portion of the conduit adjacent the tank.

4. In a furnace for coating wire with metal, a tank for containing a coating metal, a conduit adapted to contain an annealing bath and opening into said tank below the upper edge thereof, a flue surrounding said conduit, a fire box communicating with said flue near the end thereof remote from the tank and flues communicating with the above named flue and extending beneath said tank for heating the same.

5. In a furnace for coating wire with metal, a tank for containing a coating metal, a conduit adapted to contain an annealing bath and opening into said tank below the upper edge thereof, a flue surrounding said

- conduit, a fire box communicating with said flue near the end thereof remote from the tank, flues communicating with the above-named flue and extending beneath said tank 5 for heating the same, and means intermediate the first said flue and the tank for cooling the conduit adjacent the tank.
6. In a furnace for coating wire with metal, a tank, a conduit communicating therewith below the upper edge thereof, means for heating said conduit to an annealing temperature at a portion thereof remote from the tank, means for cooling said conduit at the portion thereof adjacent the tank 10 and means for heating said tank.
7. In a furnace for coating wire with metal, a tank adapted to contain the coating metal, a conduit communicating at one end with said tank below the upper edge thereof 15 and extending upwardly from its point of communication with said tank, a fire box adjacent one end of said conduit, a flue surrounding said conduit and communicating with the fire box, a flue communicating with the first said flue and extending beneath the tank, an air flue arranged between the first 20 said flue and the tank and adapted to cool the conduit adjacent the tank, said air flue communicating with the fire box.
- 25 8. In a furnace for coating wire with metal, a tank adapted to contain the coating metal, a conduit communicating at one end with said tank below the upper edge thereof and relatively raised at its other end, a fire box adjacent one end of said conduit, a flue surrounding said conduit and communicating with the fire box, a flue communicating with the first said flue and extending beneath the tank, an air flue arranged between 30 the first said flue and the tank and adapted to cool the conduit adjacent the tank, said air flue communicating with the fire box, and an auxiliary fire box beneath the tank and adapted to heat the same.
- 35 9. A galvanizing furnace comprising a galvanizing tank, a series of tubes communicating with the lower part thereof, means for heating the galvanizing tank and the tubes, the latter being provided with longitudinal partitions.
- 40 10. A furnace for galvanizing wire and the like comprising a galvanizing tank, a series of wire conduits connected to said tank, a heating chamber inclosing said conduits, a fire box connected to said heating chamber, an air inlet flue located between 45 said tank and said heating chamber and ex-

tending to said fire box and flues connecting the heating chamber and the stack and passing beneath the tank.

60

11. A galvanizing furnace comprising a galvanizing tank, a heating chamber, a series of wire conduits extending through the heating chamber and connected to the tank, an air inlet flue between the heating chamber and tank and connection therefrom to a point in the lower part of the fire box, a flue extending from the heating chamber and directly beneath the galvanizing tank and a stack connected to said flue.

65

12. In a galvanizing furnace comprising a tank, a conduit communicating with the tank beneath the top thereof and extending at its other end to a point above the level of the point of its entry to the tank and 70 means for heating the tank and conduit.

75

13. A galvanizing furnace comprising a galvanizing tank, a conduit communicating therewith, a longitudinally extending partition in the conduit for dividing it into separate chambers and means for heating the 80 conduit and tank.

80

14. A galvanizing furnace comprising a tank, a conduit communicating with the same at the lower portion thereof and extending to a higher level than the point of its communication, a bath of heavier non-adherent material occupying the lower portion of said tank and conduit and adapted to support a bath of coating metal super-natant upon the aforesaid bath and means for heating the tank and conduit.

85

15. A galvanizing furnace comprising a tank, a conduit communicating with the lower portion thereof at one end and extending at its other end to a point above the point of its communication with said tank and guides in the upper portion of the tank arranged to direct the wire in a substantially horizontal path through the tank.

95

16. A furnace for galvanizing wire comprising a galvanizing tank, a conduit communicating therewith, a heating chamber surrounding the conduit, a fire box communicating with said heating chamber at one end, a flue communicating with the heating chamber at its other end and extending beneath the galvanizing tank and a supplemental fire box connected to said flue.
